GRINDING WHEEL FEEDING MECHANISM

Carl G. Flygare, Worcester, Mass., and Homer L. Swainey, Shaker Heights, Ohio, assignors to Norton Company, Worcester, Mass., a corporation of Massachusetts

Application August 17, 1945, Serial No. 611,144

4 Claims. (Cl. 51—165)

1

The invention relates to grinding machines, and more particularly to a control mechanism for a hydraulically operated grinding wheel feeding mechanism.

One object of the invention is to provide a simple and thoroughly practical hydraulically operated grinding wheel feeding mechanism for grinding machines. Another object of the invention is to provide a wheel feed controlling mechanism which is arranged so that the grinding wheel may be fed rapidly so as to move into operative engagement with the work, then to be reduced to a slow predetermined grinding feed.

Another object of the invention is to provide a hydraulic piston and cylinder to move the wheel slide rapidly to and from an operative position combined with a dash pot feed regulator to slow down the rapid approaching movement of the grinding wheel to a slow predetermined grinding feed. Another object of the invention is to provide means for positively returning the dash pot piston to an inoperative position and thereby positively fill the dash pot cylinder chambers with fluid during the idle stroke of the grinding wheel slide so that the dash pot chambers are filled, ready for the next feeding operation.

Another object of the invention is to provide a single control valve which serves to control the admission of fluid to and from the hydraulic feeding cylinder when in a position to cause a movement of the grinding wheel to an inoperative position and which also serves to convey fluid under pressure from the fluid pump into the dash pot cylinder chambers to return the dash pot pistons to an inoperative position and rapidly fill the dash pot cylinder chambers with fluid for the next grinding operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of this invention, the drawing is a combined sectional view through a grinding machine wheel feeding mechanism and a piping diagram of the hydraulic feed controlling mechanism.

A grinding machine has been illustrated in the drawings comprising a base 10 which supports a longitudinally movable work supporting table

2

11 on the usual flat way 12 and V-way 13 so that the table 11 may be readily moved lengthwise of the base 10 to position a work piece in the desired operative relation with a grinding wheel.

5 The table 11 serves as a support for a headstock 14 having a headstock center 15 and a footstock (not shown) rotatably to support a work piece to be ground.

The base 10 also supports a transversely movable wheel slide 20 on the usual well known V-way and flat way (not shown). The wheel slide 20 is provided with a rotatable grinding wheel 21 which is mounted on one end of a wheel spindle 22. The wheel spindle 22 is journaled

15 in suitable bearings (not shown) in the wheel slide 20. A driving mechanism is provided for driving the grinding wheel 21 comprising an electric motor 23 mounted on the upper portion of the wheel slide 20. The motor 23 is provided with an armature shaft 24 having a multi-V-groove pulley 25 mounted on its outer end. The multi-V-groove pulley 25 is connected by multiple V-belts 26 with a multi-V-groove pulley 27 which is mounted on the outer end of the wheel

25 spindle 22.

A feeding mechanism is provided for adjusting the position of the wheel slide 20 transversely relative to the base 10 comprising a half nut 30 depending from the under side of the wheel slide

30 20. The half nut 30 meshes with a rotatable feed screw 31 which is rotatably journaled in suitable bearings in the base 10. The right-hand end of the feed screw 31 is rotatably journaled in a slidably keyed sleeve 32 which is slidably mounted in a cylindrically shaped aperture 33 which is fixed relative to the base 10. The left-hand end of the feed screw is slidably keyed within a hollow end portion 34 of a rotatable shaft 35.

The shaft 35 is journaled in a bearing 36 which is fixed relative to the machine base 10. The other end of the shaft 35 is journaled in a suitable bearing (not shown) which is fixed relative to the base 10. A suitable manually operable feed wheel 36 having the usual and well known

45 micrometer adjusting mechanism 37 is mounted on the front of the machine base and is operatively connected to rotate a gear 38 which is mounted on the outer end of the shaft 35. It will be readily apparent from the foregoing disclosure that a rotary motion of the feed wheel

50 36 will be transmitted to rotate the feed screw 31 and thereby transmit a transverse movement to the wheel slide 20 and the grinding wheel 21.

In order to provide a rapid approaching and receding movement of the grinding wheel, a

hydraulically operated mechanism is provided for rapidly moving the wheel slide 20 to and from an operative position comprising a hydraulic cylinder 40 which is fixed relative to the base 10. The cylinder 40 contains a slidably mounted piston 41 which is connected to a double end piston rod 42. The double end piston rod 42 projects through the cylinder heads at both ends of the cylinder 40. The left-hand end of the piston rod 42 is connected to the slidably mounted sleeve 32. The piston rod 42 is preferably arranged in axial alignment with the feed screw 31. When fluid under pressure is admitted through a pipe 43 into a cylinder chamber 44, the piston 41 will be moved toward the right to move the wheel slide 20 and grinding wheel 21 also in a direction toward the right to an inoperative position. During this movement fluid within a cylinder chamber 45 is exhausted through a pipe 46.

A hydraulic control system is provided for supplying actuating fluid under pressure to the cylinder 40. This mechanism may comprise a motor driven fluid pump 50 which draws fluid through a pipe 51 from a box-like reservoir 52 which, as illustrated, is formed within the base 10 of the machine. The pump 50 forces fluid under pressure through a pipe 53 to a control valve 54. A variable pressure relief valve 55 is connected in the pipe line 53 to facilitate maintaining the desired operating pressure in the hydraulic system. The relief valve 55 serves to return excess fluid under pressure directly to the reservoir 52 and thereby to maintain uniform pressure within the hydraulic system.

The control valve 54 is preferably a piston type control valve comprising a valve stem 56 which is provided with a plurality of integrally formed valve pistons 57, 58, 59, 60 and 61. A manually operable control lever 62 is pivotally supported on a stud 63 which is supported by a bracket 64 fixed on the front of the machine base 10. The control lever 62 is connected by means of a pin 65 with a slot 66 formed in the valve stem 56. By manipulation of the control lever 62, the valve stem 56 may be shifted from one extreme position to the other. In the full line position illustrated in the drawing, the valve stem 56 is shown in its rearward or right-hand end position to maintain the wheel slide 20 and grinding wheel 21 in a rearward or inoperative position. When it is desired to cause a forward feeding movement of the grinding wheel 21, the control lever 62 is moved in a counterclockwise direction into broken line position 62a to shift the valve stem 56 into its extreme left-hand position.

Fluid under pressure passing through the pipe 53 enters a valve chamber 70 formed between the valve pistons 59 and 60 and in the position illustrated fluid under pressure within the chamber 70 passes out through the pipe 43 into the cylinder chamber 44 to move and maintain the piston 41 in a right-hand end or inoperative position. During this movement of the piston 41, fluid exhausting from the cylinder chamber 45 through the pipe 46 enters a valve chamber 72 located between the valve pistons 58 and 59 and passes out through an exhaust pipe 73 into the reservoir 52. A manually operable throttle valve 74 is provided in the pipe line 73 to facilitate controlling the rate of exhaust of fluid from the cylinder chamber 45 and thereby to control the rate of movement of the wheel slide 20 and the grinding wheel 21 to an inoperative position.

When it is desired to initiate a forward feeding movement of the grinding wheel 21, the lever

62 is moved in a counterclockwise direction to position the valve stem 56 in its extreme left-hand end position, in which position fluid under pressure entering the valve chamber 70 will pass through the pipe 46 into the cylinder chamber 45 to cause the piston 41, the wheel slide 20, and the grinding wheel 21 to move toward the left rapidly to approach the work piece to be ground. During the forward feeding movement, fluid within the cylinder chamber 44 exhausts through the pipe 43 into a valve chamber 75 located between the valve pistons 60 and 61 and pass outwardly through the exhaust pipe 73 and the throttle valve 74 into the reservoir 52. It will thus be seen that the throttle valve 74 may be adjusted to control the rate of the rapid approaching and rapid receding movement of the grinding wheel 21.

In order to slow down the rapid approaching movement of the grinding wheel 21 to a slower predetermined grinding feed, a dash pot feed regulator 80 is provided comprising a pair of dash pot cylinders 81 and 82 which are arranged on diametrically opposite sides of the rearwardly extending portion of the piston rod 42. The dash pot cylinders 81 and 82 are provided with dash pot pistons 83 and 84, respectively. Compression springs 85 and 86 may be provided normally to urge the dash pot pistons 83 and 84 in a direction toward the right.

The rearward or right-hand end of the piston rod 42 is provided with a threaded portion 87 having an adjustable collar 88 supported thereon. When the piston 41 is moved toward the left rapidly to position the grinding wheel 21, the rapid movement continues until the collar 88 engages the left-hand end of a sleeve 89 which is supported on the piston rod 42. The sleeve 89 is provided with a flanged portion 90 which is fixedly mounted on the sleeve 89 or may be formed integral therewith if desired. The flange 90 is arranged in operative engagement with the right-hand ends of both of the dash pot pistons 83 and 84, respectively. As the collar 88 engages the sleeve 89, continued movement of the piston 41 causes the flange 90 to start movement of the dash pot pistons 83 and 84 toward the left. This movement serves to force fluid out of the dash pot cylinders 81 and 82. By controlling the exhaust of fluid from the dash pot cylinders 81 and 82 by means of a needle valve 91, the rapid approaching movement of the grinding wheel 21 may be slowed down to the desired and predetermined grinding feed. Fluid exhausting through the needle valve 91 passes through a pipe 92 and returns to the reservoir 52. An adjustably mounted stop screw 93 is provided to determine the right-hand end position of the flange 90 and the dash pot pistons 83 and 84.

It is desirable to provide a suitable means for rapidly returning the dash pot pistons 83 and 84 to their rearward or inoperative positions when the grinding wheel 21 is moved to an inoperative position after a grinding operation has been completed. As illustrated in the drawings, fluid under pressure from pump 50 passing through the pipe 53 may also pass through a pipe 95, through a throttle valve 96, through a variable pressure control valve 97, into a valve chamber 98 located between the valve pistons 57 and 58. In the position of the valve 54 as illustrated, fluid under pressure entering the valve chamber 98 passes outwardly through a pipe 99 directly into the dash pot cylinders 81 and 82 both of which are interconnected by a transversely extending passage 100 formed in a dash pot cylinder head

101 at the left-hand end of the dash pot assembly. It will be readily apparent from the foregoing disclosure that when the control valve 56 is shifted into the position illustrated, fluid will be admitted to the cylinder chamber 44 to cause a rapid movement of the piston 41, the wheel slide 20 and the grinding wheel 21 toward the right to an inoperative position. At the same time, fluid under pressure will be passed through the pipe 99 into the dash pot cylinders 81 and 82 rapidly to return the dash pot pistons 83 and 84 to a right-hand or inoperative position and thereby rapidly fill the dash pot cylinder chambers 81 and 82, ready for the next infeeding movement. The variable pressure control valve 97 is provided so that if desired the pressure applied to return the dash pot pistons 83 and 84 to their inoperative position may be at a lower pressure which is independent of the pressure within the main hydraulic system.

In certain grinding operations, it is desirable to feed the grinding wheel 21 into the work to reduce it to approximate size, after which the feeding movement of the grinding wheel 21 is further slowed down or reduced to an extremely fine feed just prior to positively stopping the infeed by engagement of the stop collar 106 with the stop surface 104. This may be accomplished by providing an adjustable throttle valve 103 in the pipe line 102 which is arranged to control the exhaust of fluid from the dash pot cylinders 81 and 82 after the port leading to the needle valve 91 is closed by the forward movement of the dash pot piston 83. It will be readily apparent from the foregoing disclosure that the valve 103 may be entirely closed, in which case the needle valve 91 will control the entire infeed of the grinding wheel or, when desired the throttle valve 103 may be opened to the desired extent so that after closing of the port leading to the needle valve 91, the valve 103 will control the exhaust of fluid from the dash pot cylinders 81 and 82, thus facilitating an extremely fine precise feed movement of the grinding wheel at 21.

It will be readily apparent that when the lever 62 is shifted in a counterclockwise direction into position 62a to initiate a grinding feed, the valve piston 56 will cut off the fluid passing through the pipe 99 and hold fluid in the pipe 99 and dash pot cylinders 81 and 82, respectively, so that on the next forward feeding movement the piston 41 will rapidly cause an approaching movement of the grinding wheel 20 until the dash pot pistons 83 and 84 start movement. When the dash pot pistons 83 and 84 start moving, fluid within the dash pot cylinders 81 and 82 is exhausted through the needle valve 91, thus retarding the rapid approaching movement caused by the piston 41 to reduce the infeeding movement from a rapid approaching to a slow predetermined grinding feed. If the throttle valve 103 is opened, a further very fine feeding movement of the grinding wheel 21 will continue until stop collar 106 engages stop surface 104.

The operation of this improved feeding mechanism will be readily apparent from the foregoing disclosure. When it is desired to initiate a grinding feed, the control lever 62 is shifted in a counterclockwise direction to shift the valve stem 56 into its left-hand end position. This movement of the valve stem serves to trap fluid within the dash pot cylinders 81 and 82 and at the same time serves to pass fluid through the pipe 46 into the cylinder chamber 45 to move the piston 41 rapidly toward the left to cause a rapid approaching movement

of the wheel slide 20 and the grinding wheel 21. The rapid approaching movement continues until the grinding wheel 21 is about to engage the surface of the work to be ground, at which point the collar 88 engages the sleeve 89, after which continued movement of the piston 41 is retarded by the dash pot pistons 83 and 84, forcing fluid from the dash pot cylinders 81 and 82 out through the needle valve 91 which controls the rate of the grinding feed until the port leading to valve 91 is closed by dash pot piston 83. The forward grinding feed continues under the control of throttle valve 103 until a positive stop collar 106 carried by the sleeve 89 engages a positive stop surface 104 formed on an end cap 105 of the dash pot 80. After the work has been ground to the desired size, the control lever 62 is again shifted in a clockwise direction into the full line position illustrated in the drawing so that fluid under pressure is passed through the pipe 43 into the cylinder chamber 44 to move the piston 41 rapidly toward the right into the position illustrated, thus rapidly moving the wheel slide 20 and grinding wheel 21 to an inoperative position. At the same time the valve stem 56 is shifted into the position illustrated, fluid under pressure is passed through the pipe 99 into the dash pot cylinder chambers 81 and 82 rapidly to return the dash pot pistons 83 and 84 into their extreme right-hand end positions and also rapidly to fill the dash pot cylinders 81 and 82 ready for the next infeeding movement.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:

- 45 1. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 50 2. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 55 3. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 60 4. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 65 5. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 70 6. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.
- 75 7. In a grinding machine having a base, a transversely movable grinding wheel slide, a rotatable grinding wheel on said slide, a hydraulic piston and cylinder to move said slide rapidly toward and from an operative position, a dash pot feed regulator including a dash pot piston and cylinder to slow down the rapid approaching movement to a predetermined relatively slow grinding feed, a control valve to control the admission of fluid to and exhaust of fluid from said hydraulic cylinder, and means including a pipe directly connecting the control valve with the dash pot cylinder to admit fluid under pressure directly from the pump to the dash pot cylinder during movement of the wheel slide to an inoperative position positively to return the dash pot piston to an inoperative position so as to rapidly fill the dash pot cylinder for the next grinding operation.

with the dash pot cylinder, said control valve being arranged to admit fluid under pressure directly from the pump through said pipe to the dash pot cylinder positively to return the dash pot piston to an inoperative position so as to rapidly fill the dash pot cylinder when the control valve is shifted to cause movement of the grinding wheel to an inoperative position.

3. In a grinding machine having a base, a transversely movable grinding wheel slide, a rotatable grinding wheel on said slide, a hydraulic piston and cylinder to move said slide rapidly toward and from an operative position, means including a fluid pump to supply fluid under pressure, a dash pot feed regulator including a dash pot piston and cylinder to slow down the rapid approaching movement to a predetermined relatively slow grinding feed, an adjustable needle valve to control the exhaust of fluid from the dash pot cylinder to regulate the grinding feed, a control valve to control the admission of fluid to and exhaust of fluid from said hydraulic cylinder, and a pipe connecting said control valve directly with the dash pot cylinder, said control valve being arranged simultaneously to admit fluid under pressure to said hydraulic cylinder to cause a rearward movement of the grinding wheel to an inoperative position and to admit fluid under pressure directly from the pump through said control valve and pipe to the dash pot cylinder positively to return the dash pot piston to an inoperative position and to fill the dash pot cylinder for the next grinding operation.

4. In a grinding machine having a base, a transversely movable grinding wheel slide, a rotatable grinding wheel on said slide, a hydraulic piston and cylinder to move said slide

rapidly toward and from an operative position, means including a fluid pump to supply fluid under pressure, a dash pot feed regulator including a dash pot piston and cylinder to slow down the rapid approaching movement to a predetermined slow grinding feed, an adjustable needle valve to control the exhaust of fluid from said dash pot cylinder so as to regulate said grinding feed, a control valve to control the admission of fluid to and exhaust of fluid from said hydraulic cylinder, a pipe connecting said control valve directly with said dash pot cylinder, said control valve being arranged when in a forward feeding position to prevent exhaust of fluid from said dash pot cylinder except through said needle valve, said control valve having an independent valve chamber which is arranged to admit fluid under pressure directly from the pump and control valve to said dash pot cylinder positively to return the dash pot piston when the control valve is in a rearward feeding position to move the grinding wheel to an inoperative position so as positively to fill the dash pot cylinder for the next grinding operation.
